UNITED STATES PATENT OFFICE.

NATHAN MARPLE LOWER, OF SCHENECTADY, NEW YORK, ASSIGNOR TO LOCOMOTIVE STOKER COMPANY, OF SCHENECTADY, NEW YORK, A CORPORATION OF PENNSYLVANIA.

LOCOMOTIVE-STOKER.

1,377,259.

Specification of Letters Patent. Patented May 10, 1921.

Application filed April 13, 1915. Serial No. 21,009.

To all whom it may concern:

Be it known that I, NATHAN M. LOWER, a citizen of the United States, and resident of Schenectady, county of Schenectady, and 5 State of New York, have invented certain new and useful Improvements in Locomotive-Stokers, of which the following is a specification, and which are illustrated in the accompanying drawings, forming a part 10 thereof.

The invention relates to that type of stokers for locomotives in which the fuel is delivered to the fire-box through the grate, being discharged at or above the level of the 15 bed of burning fuel and distributed over the top thereof.

The invention relates to means for transferring the fuel from the tender to the locomotive, delivering it into the fire-box, and 20 spreading it therein. Its objects are to secure simplicity of construction and operation; the reduction of the fuel in size when required; the moistening of the fuel before delivery to the fire-box, in order to prevent 25 the loss of its finer particles through the flues without combustion; efficient regulation of the rate of delivery; proper and variable distribution of the fuel as delivered to the fire-box; the effective spreading of 30 the fuel within the fire-box; and the protection of the parts of the apparatus which are located within the fire-box from injury by heat.

These various objects are attained by 35 means of, and the invention consists in a structure such as is hereinafter described, and as illustrated in the accompanying drawings, in which—

Figure 1 is a detail vertical section 40 through the rear end of a locomotive and its tender, with the improved stoker applied thereto;

Fig. 2 is a detail plan section of the rear 45 end of the locomotive taken above the grate of the fire-box, the cab floor being omitted;

Fig. 3 is a detail transverse vertical section 50 of the locomotive taken on the line

3—3 of Fig. 1, some of the parts being broken away and some portions within the fire-box being shown in section;

Fig. 4 is a detail section on the line 4—4 of Fig. 2;

Fig. 5 is a detail section on the line 5—5 of Fig. 1;

Fig. 6 is a detail transverse section 55 through the crusher;

Fig. 7 is a detail longitudinal section through the crusher and a portion of the conveyor;

Fig. 8 is a detail section on the line 8—8 60 of Fig. 2;

Figs. 9 and 10 are sectional details of the conveyor reversing mechanism;

Fig. 11 is a detail longitudinal section through the operating motor;

Fig. 12 is a sectional view on the line 65 12—12 of Fig. 11;

Fig. 13 is a detail of the valve casing of the motor;

Fig. 14 is a diagrammatic view of the 70 motor.

A portion of the frame of a locomotive is represented at 20, its cab or firing-floor at 21, and the rear wall of its fire-box at 22, the latter being provided with a door 75 opening 23.

The framework of the engine tender is represented at 24, and at 25 there is shown the inner wall of the tender tank which constitutes also the fuel bin. The floor of the 80 fuel bin is provided with an opening, as indicated at 26, which may be covered by means of removable plates, as is common in devices of this class. A trough 27 is located below the opening 26, and leads to the 85 forward end of the tender, delivering to the shell 28 of the fuel crusher, which discharges into a tube 29 leading under the floor 21 of the locomotive cab. This tube is connected at its forward end by means of a ball and 90 socket joint 30, with a delivery box 31 rigidly supported by the locomotive frame and leading upwardly into the fire-box through 95 the grate. The trough 27 is suitably sup-

ported in such manner as to permit the necessary longitudinal and lateral movement with reference to the frame of the tender incident to the flexure of the coupling uniting the tender to the locomotive. For this purpose there is shown a chair 68, carried by the tender frame, and a shoe 69 carried by the trough and slidingly engaging the chair.

- 10 A shaft 32 is journaled within the trough 27 and tube 29, and extends through the crusher shell 28. Upon this shaft there is mounted a spiral conveyer 33, within the trough 27, the cone 34 of the crusher, and 15 a spiral conveyer 35 within the tube 29. The crusher comprises the shell 28 which tapers toward its delivery end and is longitudinally ribbed, and the longitudinally ribbed cone 34, the smaller end of which is 20 at the receiving end of the shell. Fuel dropping through the opening 26 is advanced by the conveyer 33 to the crusher, and therethrough to the conveyer 35 which advances it to and through the box 31.
- 25 The passage through the box 31, longitudinally considered, curves upwardly, its outlet end being vertical. It is spread laterally toward its delivery end and thereby divided by a V-shaped partition 36, thereby 30 providing two discharge openings 37, 38. These openings are surrounded by a flat plate 39 which forms a ledge or table upon which the fuel forced up through the openings is received. Depending from the side 35 and front margins of the plate 39 there is a grated skirt 40 outwardly inclined and extending to the level of the surface of the fire-box grate 41.
- 30 A plurality of nipples, here shown as six 40 in number and designated by the numerals 42, 43, 44, 45, 46 and 47, rise through and slightly above the plate 39, and each is provided with one or more lateral ports 48 so directed as to discharge a fluid against the 45 mass of fuel resting upon the plate 39 and impel it over the surface of this plate and into the chamber of the fire-box. Any desired impelling fluid may be used, either in liquid or vapor form. The flat surface of 50 the plate 39 gives direction to the impelled fuel and permits its delivery to any part of the fire-box to which the impelling jet is directed, according to the force or intensity of the pressure employed.
- 55 The location of the fluid discharging nipples at the sides and in front of the feed apertures 37, 38, causes the fuel to come within their influence by a falling instead of a rising action, as would be the case if they 60 were so arranged as to discharge into the mass of fuel as it came up through the openings, and as a consequence the tendency to separate out the dust or finer particles of fuel from the coarser portions is largely obviated, thereby preventing the loss of the

fine fuel by having it carried into the furnace flues unconsumed. The grated apron 40 provides for the admission of air to support combustion and to protect, by its cooling action, the parts of the feeding mechanism which are within the firebox.

For the purpose of better distributing the fuel a V-shaped deflecting flange 49 is formed on the inner wall of each discharge branch of the passage of the box 31, adjacent its inner end, for the purpose of guiding a considerable portion of the fuel to the right and left and bringing it under the influence of the central nipples 43, 44, and the side nipples 42, 45.

For the purpose of controllably regulating the delivery of the fuel to the right or to the left sides of the fire-box, an oscillatable deflecting plate 50 is mounted within the passage of the box 31 below the partition 36, 85 being carried by a shaft 51, one end of which projects backwardly into the cab of the locomotive and is provided with means for effecting its oscillation. Normally this deflecting plate will occupy a central position 90 and the fuel will ascend in equal volumes through the two branches of the box passage. Should it be found desirable to vary the delivery, diminishing the supply at one side and increasing it at the other side of 95 the fire-box, the plate 50 is swung to the right or to the left, thereby cramping one branch passage and enlarging the other. Any suitable controlling mechanism for oscillating the shaft may be employed. There 100 is shown for this purpose a worm gear 52, fixed upon the shaft 51, and a worm shaft 53 meshing therewith and being provided with a hand lever 54. While the deflecting plate is shown in connection with a feed conduit having two outlets, it is obvious that its 105 action is not dependent upon the presence of the partition 36 but that without it the plate may be used to vary the relative delivery of fuel to the right or left side of the 110 conduit, and consequently of the fire-box.

The box 31 is protected from the extreme furnace heat by air passing upwardly around it and into the fire-box through the perforations in the grated apron 40, and 115 also by the fluid used for spreading the fuel in the fire-box. As a further means for protecting the plate 39 and the upper edges of the box 31, the plate is shown as provided with a depending flange 55, which is offset 120 inwardly to meet the walls of the box, thus, with the partition 36, constituting a conduit 56 along three sides of each of the fuel discharge apertures. This conduit is open to the ash-pit at its ends, the flange 55 terminating 125 a short distance from the front wall of the fire-box, as indicated by dotted lines at 57. A nipple 58 is located within the chamber 56, and preferably between the openings 37, 38, and is supplied with a cooling fluid 130

through a pipe 59 leading from any suitable source of supply. Fluid discharged from the nipple 58 is therefore driven through the passage 56 and discharged at both ends 5 thereof into the ash-pit.

The nipples 42 to 47 are supplied with the impelling fluid through a pipe 60 leading from any suitable source of supply, and being connected with the several nipples by 10 means of branches, as 61, 62, 63. The impelling fluid may be controlled by any suitable means and delivered either continuously or intermittently, as may be desired. The controlling means may be a simple 15 valve, as indicated at 60^a.

The box 31 is provided with a cleaning door 64, located at the bend of its passage and opening into the ash-pit of the locomotive. This door may be controlled by means 20 of a pull rod 65 extending through the cab floor, and being attached to one arm of a bell-crank lever 66 suitably mounted on the locomotive frame, the other arm of the bell-crank being suitably connected with the door 25 64, as by means of a link 67.

When a fuel is employed which is in part finely pulverized, it is desirable to moisten it as a further means for preventing the dust from being carried off unconsumed. 30 For this purpose a pipe 70 may lead from any suitable source of supply into the passage of the box 31, in order that steam or water may be introduced into the mass of fuel.

35 The shaft 32 is driven by means of a jointed and extensible shaft 71, the forward end of which is journaled on the locomotive frame and the rearward end of which is journaled in a box 72 carried by the trough 40 27. A pinion 73, mounted on the rear end of the shaft 71, drives the gear wheel 74 mounted on the rear end of the shaft 32 through an idler 74^a. A gear wheel 75 meshes with a rack 76, and is fixed upon a short shaft 77 45 which is connected to the shaft 71 by a ratchet and pawl mechanism, whereby the latter shaft is driven in one direction only.

The ratchet and pawl mechanism comprises a shell or casing 78, fixed upon the 50 shaft 77 and carrying a pair of pawls 79, 80, for coöperating with a ratchet wheel 81 fixed upon the shaft 71, the end of which enters a socket in the end of the shaft 77, and drives the shaft 71 in the direction to impart to the 55 screw conveyer its feeding action. Should the conveyer become clogged, as by the presence of extraneous matter in the fuel, the direction of the screw may be reversed by throwing the pawl 79 out of and the pawl 80 into operative relation with the ratchet wheel 81. This is accomplished by means of a pawl-lifting finger 82, interposed between the two pawls and to which the latter are held in engagement by means of a 60 retractile spring 83 connecting them. The 65

pawl-lifting finger is carried by an oscillatable plate 84, mounted in one disk face of the casing 78. A lever 85, fulcrumed at 86 upon the casing 78, so as to swing in a plane perpendicular to the axis of the rotating 70 parts, is provided with a finger 87 loosely entering an aperture in the plate 84.

The parts are so disposed that when the free end of the lever 85 is in the position nearest to the shaft 71, in which position it 75 is normally held by means of a spring 88, the pawl 79 is active and the pawl 80 is raised. A conical cam block 89, slidingly mounted on the shaft 71, engages the free end of the lever 85 to move it outwardly. 80 This cam-block is actuated by means of a lever 90, controlled by a pull handle 91 located in position to be convenient of access, and having notches, as 92, for engaging a suitable holding lug. 85

The motor comprises a cylinder 93, within which reciprocates the piston 94, to the stem of which the rack 76 is attached. Referring to the diagrammatic view Fig. 14, live steam is supplied to the motor through the port 95 90 in the valve casing 96. The steam is distributed by means of a D valve 97, coöperating with the cylinder ports 98, 99, and an exhaust port 100. The valve 97 is carried by a rod 101, on the ends of which are mounted 95 pistons 102, 103, differentiated in size, and between which the live steam enters through the port 95. The valve 97 is normally held in the position shown by reason of the preponderating pressure on the piston 103. 100 The valve is shifted by the admission of steam to the outer side of the piston 103, through a lead 104 from the valve casing, this casing being ported to the atmosphere back of the piston 102, as shown at 105. 105

The admission of steam to the outer face of the piston 103 is controlled by a D valve 106, carried by a rod 107 reciprocating within a suitable casing over induction and exhaust ports 108, 109. The rod 107 is moved 110 by the motor piston 94 in the manner indicated in Fig. 3, which shows the several parts in their proper relation. The piston rod 110 of the motor is tubular throughout a portion of its length, and receives the rod 110 107, which has upon its end a button 111. On the outstroke of the piston 94 this button is engaged by a plate 112, through which the rod plays, and which is secured to the piston, the valve 106 being thereby moved 120 to the position shown in Fig. 14, opening the exhaust port 109 and permitting a shifting of the valve 97 to the position shown, for the purpose of delivering steam to the opposite end of the cylinder 93 and effecting the 125 return stroke. As the piston 94 completes its return or instroke, the button 111 is engaged by the bottom of the bore of the piston rod 110, and the valve 106 is shifted to close the exhaust and open the induction 130

port 108, whereupon the valve 97 is moved to the left, admitting steam through the port 98 for the next piston stroke.

The speed of the motor is regulated by delaying its return stroke. This is accomplished by means of a cutoff valve 113 controlling the port or duct 99, leading to the farther end of the cylinder. The stem of this valve extends into a cylinder 114, and is attached to a piston 115 reciprocating therein. A spring 116, reacting between this piston and the inner end of the cylinder, tends to hold the valve normally open. A duct 117 leads from the duct 99 to the outer end of the cylinder 114, closing the valve against the resistance of the spring 116 when the valve 97 is in the position shown in Fig. 14. A by-pass 118 connects the opposite ends of the cylinder 114, and is choked by means of a needle-valve 119. When the pressure is equalized on the two faces of the piston 115, the valve 113 is opened by the action of the spring 116. By reason of the choking of the by-pass 118, an interval elapses after steam is admitted to the cylinder 114 through the duct 99 before this equalization takes place, and during this interval the valve 113 is, of course, held firmly to its seat. The length of this interval is determined by the position of the needle valve 119. An indicating finger 120, over which plays the hand wheel 121 on the needle-valve stem 122, enables the operator to readily set the valve to secure any desired engine speed, and when this valve is set the motor continues to operate at such speed uniformly. When the motor is operated at a high speed, the quick closing action of the valve 113 is essential, and is secured by providing a relief valve 123 to permit the free escape of fluid from the front end of the cylinder within which the piston 115 reciprocates, when the passage 99 is open to the exhaust.

I do not desire to be understood as limiting myself to the particular embodiment of the invention herein shown and described, as various modifications can be made within its scope.

As shown and described, there are no working parts exposed to the furnace heat. The invention is, however, of sufficient scope to include any inside and through the grate feed in which the fuel is introduced at a plurality of points in the fire-box, thereby equalizing its distribution.

I claim as my invention—

1. In a locomotive stoker, in combination, a locomotive having a fire-box, a tender having a coal bin, a conveyer located below the floor of the tender and receiving from the bin thereof, a receptacle on the locomotive receiving from the conveyer, a conduit leading from the receptacle upwardly through the bottom of the fire-box, a table

extending laterally from the discharge end of the conduit, a grated skirt depending from the margins of the table and means for sweeping fuel from the surface of the table.

2. In a locomotive stoker, in combination, a locomotive having a fire-box, a tender having a coal bin, a conveyer located below the floor of the tender and receiving from the bin thereof, a receptacle on the locomotive receiving from the conveyer, a conduit leading from the receptacle upwardly through the bottom of the fire-box, a table extending laterally from the discharge end of the conduit, and a nipple adapted to discharge a propelling jet of fluid over and contiguous to the upper surface of the table.

3. In a locomotive stoker, in combination, a locomotive having a fire-box, a tender having a coal bin, a conveyer located below the floor of the tender and receiving from the bin thereof, a receptacle on the locomotive receiving from the conveyer, a plurality of conduits leading from the receptacle upwardly through the bottom of the fire-box, a laterally extending plate at the discharge ends of the conduits, and nipples located above the plate at each side of each conduit, each being adapted to discharge a propelling jet of fluid over and contiguous to the plate surface.

4. In a locomotive stoker, in combination, a locomotive having a fire-box, a tender having a coal bin, a conveyer located below the floor of the tender and receiving from the bin thereof, a receptacle on the locomotive receiving from the conveyer, a conduit leading from the receptacle upwardly through the bottom of the fire-box, a table extending laterally from the discharge end of the conduit, and means for forcibly sweeping fuel from the plate.

5. In a locomotive stoker, in combination, a locomotive having a fire-box, a tender having a coal bin, a conveyer located below the floor of the tender and receiving from the bin thereof, a receptacle on the locomotive receiving from the conveyer, a conduit leading from the receptacle through the grate of the bottom of the fire-box, a reciprocating fluid motor, means for transmitting driving power to the conveyer from the motor in one direction of movement of its piston, and means for reversing the conveyer for moving fuel backwardly in the conduit.

6. In a locomotive stoker, in combination, a locomotive having a fire-box, a conduit for delivering fuel upwardly through the bottom of the fire-box, a tender having a fuel bin, a conveyer located below the bin and forcibly feeding fuel to and through the conduit, and a cone and shell fuel crusher forming a section of the conveyer conduit.

7. In a stoker, in combination, a fire-box

having a grate, a fuel conduit discharging through the grate, a fuel supporting plate extending laterally from the discharge end of the conduit, and fluid discharging nipples delivering over the surface of the plate.

8. In a locomotive stoker, in combination, a conduit leading upwardly through the bottom of the fire-box, means for forcing fuel upwardly through said conduit, a laterally extending table at the outlet of the

conduit adapted to receive fuel therefrom, and means to sweep fuel from the table and distribute the same over the grate comprising nipples projecting upwardly from the table adapted to direct a propelling jet of 15 fluid thereover.
